H. E. LARSON

FENCEPOST

Filed June 22, 1926

UNITED STATES PATENT OFFICE.

HENRY E. LARSON, OF BOYD, MINNESOTA.

FENCE POST.

Application filed June 22, 1926. Serial No. 117,834.

This invention relates to fence posts, and one object of the invention is to provide a fence post which may be firmly anchored in the ground and prevented from tilting out 5 of a vertical position.

Another object of the invention is to provide the post with an anchor which may be readily applied and securely held to the post with its end portions projecting transversely 10 therefrom.

Another object of the invention is to provide a post to which wire-securing staples may be readily applied and securely locked in place.

15 This invention is illustrated in the accompanying drawing, wherein

Figure 1 is a view showing the improved fence post in elevation;

Fig. 2 is a fragmentary sectional view 20 taken on the line 2—2 of Fig. 1 with a staple applied to the post;

Fig. 3 is a transverse sectional view through the post taken on the line 3—3 of Fig. 1;

25 Fig. 4 is a longitudinal sectional view through the post and anchor taken on the line 4—4 of Fig. 1;

Fig. 5 is a view of the anchor before being applied to the post, and

30 Fig. 6 is a transverse sectional view taken on the line 6—6 of Fig. 1.

The fence post, which is indicated in general by the numeral 1, is formed of metal and preferably consists of a length of T 35 bar having a web 2 projecting from its main portion approximately midway its side edges. In actual practice the bar from which the post is formed is preferably three inches wide and the web two inches wide so that, when the post is driven into the ground 40 and the dirt packed about its body portion and web, it cannot be readily moved out of a vertical position. Sets of openings 3 are formed in the post adjacent its side edges 45 and the sets of openings at one side of the post are disposed in staggered relation to the openings at the other side so that the body portion of the post will not be unduly weakened. These openings are to receive 50 staples, by means of which the fence wires are secured to the post. Referring to Fig. 2, it will be seen that the openings 3 of each set converge from the outer face of the post toward its rear face so that, when a 55 staple 4 is driven into place in straddling relation to a fence wire 5, the arms of the

staple will project from the rear face of the post in crossed relation to each other and very firmly lock the staple to the post. The staples will, therefore, be prevented from 60 working loose and there will be no danger of the wires becoming detached from the post and sagging. When it is desired to remove a wire, it is merely necessary to cut the head of the staple with a pair of pliers 65 or the like and the two staple sections may be readily moved through the openings.

The anchor 6 by means of which the post is braced to prevent it from being moved out of a vertical position by horses or cattle 70 pushing against a post or the wires of the fence is preferably formed of strong sheet metal and is of such length that when it is secured to the post its end portions will provide wings which project from the sides of the post. The anchor plate is passed through a slot 7 formed in the web for a portion of its length at its junction with the body portion of the post and the slot is 75 formed of greater length than the depth of the anchor plate so that the anchor plate may be readily passed through it and a portion of the web at the lower end of the slot seated in the notch or recess 8 which leads 80 from the lower edge of the anchor plate. Tongues 9 project from the upper end of the intermediate portion of the anchor plate and are spaced apart a sufficient distance to 85 permit the tongues to be bent into the notches or recesses 10 which lead from the side edges of the post. From an inspection of Fig. 1, it will be apparent that when the web of the post is seated in the notch 8 and the tongues 9 are bent into the notches 10 the anchor will be very firmly secured to the 90 post and will be prevented from having movement either longitudinally or transversely of the post. Therefore, the anchor plate will be prevented from working loose 95 from the post and will serve very effectively to brace the post and prevent it from being worked loose from the ground. It should also be noted that from the notches 10 to its upper end the side portions 11 of the post are curved, as shown in Fig. 6, so that a 100 fence wire may be stretched without barbs carried thereby catching against the sides of the posts and preventing it from being tightly stretched.

Having thus described the invention, I 110 claim:

1. A fence post comprising a standard, a

web extending from said standard intermediate the width thereof and formed with a slot adjacent the standard, and an anchor passed through said slot transversely of the 5 standard and provided with tongues, the side portions of said standard being provided with notches forming seats and said tongues being bent to extend through the seats and engage the opposite face of the 10 standard from the anchor to securely interlock the anchor with the post.

2. A fence post comprising a standard, a web extending from a face of said standard intermediate the sides thereof and formed

with a slot adjacent the standard, and an 15 anchor plate passed through said slot transversely of the standard in engagement with the said face thereof and provided with tongues bent into engagement with the side edge faces of the standard and opposite face 20 of the standard from the anchor plate, said anchor plate being formed with a notch leading from its lower edge and receiving a portion of the web at the bottom of the slot.

In testimony whereof I affix my signature. 25

HENRY E. LARSON. [L.S.]
